(57) CLAIM

The ornamental design for a handbag as shown and described.

DESCRIPTION

1. Handbag

1.1 : Perspective

1.2 : Front

1.3 : Back

1.4 : Left

1.5 : Right

1.6 : Top

1.7 : Bottom

The evenly dashed broken lines in the drawings constitute stitching on the handbag, and form part of the claimed design.
